(57) **CLAIM**

The ornamental design for a building material, as shown as described.

DESCRIPTION

FIG. 1 is a front perspective view of a first embodiment of a building material showing our new design;

FIG. 2 is a top view thereof;

FIG. 3 is a left side view thereof, the right side view being a mirror image of the left side view;

FIG. 4 is a bottom view thereof;

FIG. 5 is a front view thereof;

FIG. 6 is a back view thereof;

FIG. 7 is a front perspective view of a second embodiment of a building material;

FIG. 8 is a top view thereof;

FIG. 9 is a left side view thereof, the right side view being a mirror image of the left side view;

FIG. 10 is a bottom view thereof;

FIG. 11 is a front view thereof;

FIG. 12 is a back view thereof;

FIG. 13 is a perspective view of the second embodiment of the building material seen in FIGS. 7-12 coupled together with another building material in a condition of use thereof; and,

FIG. 14 is a side view thereof.

The paired breakaway lines seen in FIGS. 1-6 indicate that anything between the break lines forms no part of the claimed design.

Features shown in broken lines show environmental structure as well as portions of the building material that form no part of the design as claimed.
